DRILLING METHOD FOR MINING THIN
ORE BODIES

Robert T. Macaul, New York County, N.Y., and Daniel J. Donovan, Clifton, N.J., assignors to Ingersoll-Rand Company, New York, N.Y., a corporation of New Jersey

Continuation of application Ser. No. 136,491, Sept. 7, 1961. This application Aug. 24, 1962, Ser. No. 219,333
6 Claims. (Cl. 299—11)

This application is a continuation of U.S. patent application Serial No. 136,491, filed September 7, 1961, by Robert T. Macaul and Daniel J. Donovan, and entitled Method of Extracting and Recovering Minerals from Veins Thereof.

This invention relates to methods of drilling and particularly to methods for mining very thin ore bodies.

In certain sections of the earth there are vast deposits of valuable ore in very thin veins ranging from less than one inch to perhaps six inches or more in thickness which have been profitably mined largely because of low labor costs. The systems employed for removing the ore have been to excavate not only the material from the vein but material above and below to a depth which would enable the miner to enter to follow the vein. Often, the vein itself is of a very hard material such as quartzite and the like and the strata in which the vein lies is likewise hard. Drilling is usually employed to form blast holes and is followed by the usual blasting and mucking operations. Obviously, this entails much labor and loss of time while blasting and mucking and cleaning up the valuable metal bearing dust as fine cuttings. In addition a great deal of material of no value whatsoever has to be removed from the mine and in addition, the roof of the excavation has to be supported to prevent caving. Also it can happen that the blasting pulverizes the ore to such an extent that it is difficult or sometimes impossible to recover.

It is an object of this invention to eliminate many of the operations above referred to and to limit as far as may be possible the excavation to removal of the valuable vein material and such of the adjacent rock of value.

In the improved embodiment of this invention the elimination of the numerous drilling operations is accomplished by a continuous process of drilling holes that embrace all of the valuable material and very little else.

In order to set up the equipment for proceeding with this method a shaft is sunk from the surface to the level of the vein and a drift is excavated along the face of the ore vein any convenient length depending upon the extent of the mine property. Then drifts are excavated transverse to the first drift preferably parallel to each other and at convenient intervals as for instance one hundred feet. The transverse drifts are excavated at the slope of the ore body and are of suitable dimensions to accommodate a drill directed at the vein. Holes are drilled by a drill rig centering on the vein and of a diameter to overlap it. Drilling proceeds until the drill hole reaches the next adjacent transverse drift.

Preferably, the drilling is done with a core drill and preferably of a type delivering hammer blows to the bottom of the hole. This is generally advantageous because the rock is chipped out in relatively large pieces and the drilling proceeds faster. As the drilling proceeds, from time to time additional lengths of core barrel have to be added and, if desired, the core may be extracted periodically and passed directly into a suitable car which when loaded can be removed and replaced by an empty. The dust and chips formed by the drilling contain valuable ore often the most valuable and are collected by vacuum apparatus depositing the same in a filter which may be separate or if desired integral with the car carrying away

2

the cores. Upon completion of the first hole, successive holes parallel to the first are drilled and preferably they overlap so as to remove all of the vein material. The system is continuous, the only interruption being due to the extension of the transverse drifts which may require blasting and mucking operations. However, such extensions of the drifts can be carried on, while the ore extraction process continues in others, so that for all practical purposes the process is continuous.

10 A suitable layout for carrying out the mining method is illustrated in the accompanying drawing in which

FIGURE 1 illustrates an earth section indicating the vein of ore and the shaft and drift leading to it,

15 FIGURE 2 is a diagrammatic plan of the drifts excavated and their relation to the ore vein,

FIGURE 3 shows an end view of the vein, and indicates the plan of holes to be bored for extracting the ore,

20 FIGURE 4 is a view indicating the type of apparatus employed for drilling the holes and associated machinery;

FIGURE 5 is a perspective view partly in section of an earth formation and plugging process adaptable to a modified process of drilling, and

25 FIGURE 6 is a perspective view of a rock formation to which still another modified method of drilling is applied.

Referring to the drawings the earth's surface indicated at 10 is penetrated by a vertical shaft 12 leading to the level of the vein 14 of ore to be removed. As shown, 30 near the shaft a horizontal drift 16 extends to vein 14 as it is generally considered desirable that there be a short level section to facilitate loading and handling of the material in the horizontal section. To facilitate loading and raising in shaft 12, a suitable hoist indicated at 18 is provided.

35 In FIGURE 2, as indicated, a cross drift 20 is excavated at about a point where drift 16 reaches the vein 14. Drift 20 extends any suitable length following vein 14 and preferably at an angle at which vein 14 would be level as indicated. Then, at suitable intervals of perhaps one hundred feet, in some cases, transverse drifts 22, 24 and 26 are excavated following the slope of vein 14. It is astonishing that in many places veins such as that indicated at 14 will extend for miles without material variation in their inclination.

40 As described above, this method proposes to drill a series of holes as indicated in FIGURE 3 at 28, that at 28' being indicated in process of drilling. Holes 28 overlap one another and they are of sufficient diameter to cover not only the depth of the vein 14 but additional material above and below the vein.

45 It is understood that in deposits of this kind a certain lesser amount of valuable ore exists in the strata closely adjacent the main ore body. Holes 28 will be drilled from one of the transverse drifts to the other next adjacent. Drilling straight holes is not a great problem. For one thing the greater hardness of the vein material often assists in keeping the drill centered if the drilling is by coring.

50 FIGURE 4 indicates the manner in which the apparatus is set up in a drift 24. As shown, the drill is of the rotary percussive type as shown at 30 and is provided with a long core barrel 32 extending into the hole 28' and terminating at a bit 34 set with hard metal adapted to strike the bottom of the hole and chip and abrade out cuttings. Cuttings of the type thus produced will contain valuable material which is recovered by means of a dust collector in the form of a suitable container 36 preferably held close to the mouth of the hole 28'. From container 36 the cuttings are removed by a suitable flexible tube 38 to a filter 40 fitted with a suitable vacuum pump 42. Drill 30 is adapted to be advanced on guides

which in this instance are formed by the flanges 44 of a pair of channels 46 (only one of which is shown) arranged back to back and mounted on a suitable adjustable rotatable base 47 which is slidably mounted on a bar 48. In this instance, the bar 48 is pivotally mounted at 50 on a base 52 so that its slope may be adjusted to correspond to the slope of the vein. By this arrangement a number of holes 28 can be made without moving the base 52. When moving becomes necessary, however, the wheels 54 supporting base 52 permit such moving. When a proper location of base 52 is established it is preferable to provide a solid support for which spuds 56 at the corners of base 52 can be set up while a column 58 which is likewise mounted on base 52 is adapted to further steady the assembly by clamping against the roof of the drift 24.

For convenience in carrying away the ore removed it may be desirable to provide an enclosed car 60 on suitable wheels 62 for placement at the rear of drill 30. Such a car can be adapted to receive pieces of core such as that shown at 64 and for that purpose a rearward tube 66 as a continuation of core barrel 32 can extend into the interior of car 60. Car 60 may be enclosed all around although this would not seem to be essential in view of the fact that the dust collector 36 should have cleaned the core pieces 64 of loose particles.

The drilling apparatus shown is not only useful for cutting cores between the transverse drifts but may be used to cut similar cores from the faces of the transverse drifts prior to advancing the drift. For that purpose, of course, the drill rig would be turned at an angle of 90° to the position shown in FIGURE 4 so as to cut in the direction of the drift.

In drilling operations it is quite important that the roof of the excavation be supported and this may be accomplished by insertion of suitable cylindrical plugs into the bored holes 28. In some cases the vein may be so thin that same result could be produced by occasionally skipping a hole. However, the use of concrete plugs would provide a use for the waste material excavated from the drifts as a source of crushed rock.

From the above it will be seen that this method of mining will enormously reduce the labor involved in the usual drilling operations as well as mucking. In addition, the time saved in drilling blast holes, blasting and mucking is to a large extent eliminated and the operation becomes substantially continuous.

It will be understood that the method of mining of this invention is applicable generally to a great many situations such as for instance surface deposits, for example coal stripping, asbestos mining, and many others.

In underground applications, other types of drilling may be used as indicated in FIGURE 5 and FIGURE 6.

In FIGURE 5 are indicated a line of overlapping holes 70 which may be drilled by a drill (not shown) which is adapted to enter the hole being formed and has a short bit which pulverizes all of the rock being removed. Such a drill is illustrated in Morrison U.S. Patent 2,810,549, of October 22, 1957. In using such a drill the cuttings are generally collected and they would be in this instance also. In order to block off the holes 70 already drilled they may be filled with suitable plugs 71 to prevent the entrance of excess air. The location of the holes would correspond to those illustrated in FIGURE 3.

Still another method is shown in FIGURE 6 in which at the edges, top and bottom of the seam 73 or thereabout a line of smaller holes 72 would be drilled as in the well known method of "line-hole" drilling. The core 74 remaining may be broken in any suitable manner and removed to recover the mineral of value. A suitable drill and mounting for such use is described in Slater Patent 2,213,329 of September 3, 1940. The blocking of

the vacated space by suitable plug as indicated at 75 will accomplish the result and purpose indicated above.

It is also understood that the drilling can be either "wet" or "dry." Also, the fine cuttings may be removed by blowing, sucking or washing from drill holes. The manner of collecting the cuttings can be varied at option of user.

While in accordance with the patent statutes a preferred embodiment of the present invention has been illustrated and described in detail, it is to be particularly understood that the invention is not limited thereto or thereby.

We claim:

1. A method of mining a thin vein of ore comprising sinking a shaft to the level of said vein, excavating a cross drift along said vein, excavating drifts at intervals transverse to the cross drift, drilling a series of overlapping parallel holes of diameter slightly in excess of the vein thickness and crosswise thereof between an adjacent pair of transverse drifts to include substantially all of the vein material therebetween, and collecting the material cut therefrom.

2. A method of mining a thin vein of ore comprising sinking a shaft to the level of said vein, excavating a cross drift along said vein, excavating drifts at intervals transverse to the cross drift, and core drilling a series of overlapping parallel holes of diameter slightly in excess of the vein and crosswise thereof between an adjacent pair of transverse drifts to include substantially all of the vein material, and collecting the material cut therefrom.

3. A method of mining a narrow vein of ore comprising sinking a shaft to the level of said vein, excavating a cross drift across said vein, excavating drifts at intervals transverse to the cross drift, core drilling a series of circular overlapping parallel holes of diameter slightly in excess of the vein and crosswise thereof between an adjacent pair of transverse drifts to include all of the vein material, and removing the core as the drilling progresses.

4. A method of mining a narrow vein of ore comprising sinking a shaft to the level of said vein, excavating a cross drift along said vein, excavating drifts at intervals transverse to the cross drift, core drilling a series of circular overlapping parallel holes of diameter slightly in excess of the vein and crosswise thereof between an adjacent pair of transverse drifts to include all of the vein material, and withdrawing the ore laden dust from the holes being drilled.

5. A method of mining a narrow vein of ore comprising sinking a shaft to the level of said vein, excavating a cross drift along said vein, excavating drifts at intervals transverse to the cross drift, core drilling a series of overlapping circular parallel holes of diameter slightly in excess of the vein and crosswise thereof between an adjacent pair of transverse drifts to include all of the vein material, withdrawing the ore laden dust from the holes being drilled, and removing the cores as the drilling progresses.

6. A method of mining a narrow vein of ore comprising sinking a shaft to the level of said vein, excavating a cross drift along said vein, excavating drifts at intervals transverse to the cross drift, core drilling the vein of ore between said transverse drifts to form a slot from which the vein of ore has been extracted, and inserting plugs in the core drilled holes to support the overburden.
